Primary Examiner — Adir Aronovich*Assistant Examiner* — Ramzi Almatrahi(74) *Attorney, Agent, or Firm* — Price Heneveld LLP; Scott P. Ryan(57) **CLAIM**

We claim the ornamental design for a camera, as shown and described.

DESCRIPTION

FIG. 1 is a front perspective view of a camera showing our new design;

FIG. 2 is a front elevational view of the camera of FIG. 1;
FIG. 3 is a rear elevational view of the camera of FIG. 1;
FIG. 4 is a right side elevational view of the camera of FIG. 1;
FIG. 5 is a left side elevational view of the camera of FIG. 1;
FIG. 6 is a top plan view of the camera of FIG. 1; and,
FIG. 7 is a bottom plan view of the camera of FIG. 1.

The broken lines depict portions of a camera in which the design is embodied and form no part of the claimed design.
